SWIMMING SHOE

Filed Oct. 28, 1931

INVENTOR
A. Weimer

BY HIS ATTORNEY *J. Ledermann*

UNITED STATES PATENT OFFICE

ANDREW WEIMER, OF NEW YORK, N. Y.

SWIMMING SHOE

Application filed October 28, 1931. Serial No. 571,501.

The main object of this invention is to provide a device which is adapted to be strapped to the foot of a bather or swimmer and serves as a swimming shoe to propel 5 the body thru the water in a more efficient manner.

Another object of this invention is to provide a swimming shoe which is equipped with hinged fins which are adapted to fold 10 when pulling the foot forward, and are spread when the foot is thrust rearward.

The above and other objects will become apparent in the description below in which characters of reference refer to like-named 15 parts in the drawing.

Referring briefly to the drawing, Figure 1 is a top plan view of the swimming shoe.

Figure 2 is a side elevational view of Figure 1.

Figure 3 is a cross sectional view of the 20 swimming shoe taken on line 3—3 of Figure 1.

Figure 4 is a perspective view looking at the bottom of the swimming shoe.

Figure 5 is a longitudinal sectional elevational view of the rib showing the spreader 25 latch of the shoe.

Referring in detail to the drawing, the 30 numeral 10 indicates a foot support plate which has a contour similar to the outline of a foot. A longitudinal rib 11 is securely fastened to this plate on the underside thereof. At the front of the plate toe straps 12 are secured while at the rear of the plate 35 heel harness straps 13 are anchored. The face 14 of the foot plate assumes an inclined position and is raised at the heel 15 thereof so that the swimming shoe assumes an angle while being worn.

40 The rib 11 serves as an anchoring member for a pair of flat fins 16 and 17 which are bounded by a rim 18. At the positions where the straight edges 20 of the fins meet the rims the latter are cut away on an angle, 45 as indicated by the numeral 19. The fins 16 and 17 are provided with hinge sleeves 21 which receive hinge pins 22, the latter being secured to the sides of the ribs 11.

Intermediate its length the rib 11 is provided with a recess 23 in which a lever 24 is

housed: Said lever is pivoted on a pin 25 and the lever is adapted to be swung outwardly to lie in supporting position beneath said fins. In a chamber of the rib adjacent 55 said pin a resilient finger 26 is mounted. Said finger has a ball 28 mounted thereon which is received in a detent 27 formed in the lever 24.

The device is used as a more efficient propulsion means for swimmers or the like. 60 The user stands on the foot plates 10 with the fins 16 and 17 in spread position. These fins are retained in that position by rotating the lever 24 to the position shown in Figure 4. In the process of swimming when moving the foot forward the fins are rotated about the hinges 21 to the folded position. As the stroke is reversed and the foot is 65 thrust rearward the rims 18 of the fins form water pockets and cause said fins to move to the spread position. The fins in the spread position will then propel the swimmer forward at a greater speed than would be possible without the device.

70 It is to be noted that certain changes in form and construction may be made without departing from the spirit and scope of the invention.

I claim:

75 In a swimming shoe, a foot support plate, a longitudinal rib fastened to said plate, oppositely disposed fins having hinge sleeves formed thereon, hinge pins secured to said rib receiving said hinge sleeves, a bounding rim on said fins, said rib having a recess therein, a lever pivoted on said rib positioned in said recess, said lever being adapted to be rotated to retain said fins in spread position to permit walking, and means for securing 80 said lever in inactive position in the recess.

85 In testimony whereof I affix my signature.

ANDREW WEIMER.
